UNITED STATES PATENT OFFICE.

THOMAS GAUNT, OF BROOKLYN, NEW YORK.

EVAPORATING APPARATUS.

SPECIFICATION forming part of Letters Patent No. 447,817, dated March 10, 1891.

Application filed July 18, 1890. Serial No. 359,133. (No model.)

To all whom it may concern:

Be it known that I, THOMAS GAUNT, of Brooklyn, county of Kings, State of New York, have invented an Improvement in Evaporating Apparatus, of which the following description, in connection with the accompanying drawings, is a specification, like letters on the drawings representing like parts.

This invention relates to apparatus for the evaporation and distillation of liquids, and has for its object to provide apparatus, as will be described, whereby the liquid being treated may be concentrated to any desired specific gravity.

My invention in an evaporating apparatus therefore consists in the combination, with an evaporator and a liquid-supply therefor, of an independent auxiliary or mixing chamber connected to the said liquid-supply and to the evaporator and interposed between them, a valve to control the liquor-supply, a float connected to the supply-valve and operated by the level of the liquid in the mixing-chamber, and a pump connected to the said evaporator and to the mixing-chamber and a branch pipe connected to the discharge-pipe for the pump, substantially as will be described.

Figure 1 is a diagram in elevation of an evaporating apparatus embodying my invention; Fig. 2, a detail, on an enlarged scale, of the auxiliary chamber shown in Fig. 1; Fig. 3, a side elevation of the auxiliary chamber shown in Fig. 2, looking toward the right, the said chamber being broken out to show the mixer or distributor in the said chamber; and Fig. 4, a top or plan view of the auxiliary chamber shown in Fig. 2.

Referring to Fig. 1, A represents an evaporating apparatus, which may be of any usual or desired construction, it preferably being composed of vertical rows of tubes, constituting an evaporating-surface, and a liquid-feeder located above the same, substantially as shown and described in United States Patent No. 409,572, granted to me August 20, 1889. The liquid-feeders referred to have connected to them branch pipes a , joined to a supply-pipe a' , connected to the bottom of an auxiliary chamber or vessel a^3 , preferably secured to the evaporator A in any suitable manner, the said pipe being provided with a

cock or valve a^4 , by which the supply of liquor to the liquid-feeders is controlled. The auxiliary chamber a^3 is connected by a pipe a^5 to a liquor-supply tank a^6 , the said pipe being provided with a cock or valve a^7 , by which the supply of liquor from the tank a^6 into the vessel a^3 may be positively controlled by hand.

The vessel a^3 is provided with a liquor-inlet valve, having its stem b (see Fig. 2) connected by link b' to a lever b^2 , pivoted, as at b^3 , to an upright b^4 , secured to or forming part of the vessel, the said lever being connected at one end, as by a link b^5 , to an air float or vessel b^6 , the said float being connected with the top and bottom of the vessel a^3 by rigid pipes b^7 b^8 and flexible pipes b^9 b^{10} . The weight of the float b^6 is counterbalanced, as herein shown, by a ball or weight b^{12} , which is adjustable on the lever b^2 .

The evaporator A is connected, as by a pipe c , to a pump c' , having its outlet-pipe c^2 extended up and connected to the top of the vessel a^3 , the said outlet-pipe, substantially near the pump c' , having extended from it a branch pipe c^3 , provided with a cock or valve c^4 , the said branch pipe preferably discharging into the tank or vessel c^5 .

The auxiliary chamber or vessel a^3 has located within it a distributor, (shown as a perforated plate c^6), supported by lugs c^7 , extended from the side walls of the said vessel. (See Fig. 3.)

In the operation of my improved evaporator the cock or valve a^7 is opened to permit weak liquor in the tank a^6 to flow into the auxiliary chamber a^3 , the inlet-valve for the said chamber being at such time opened by the counterbalancing-weight b^{12} . The weak liquor flows into the auxiliary chamber a^3 and into the float b^6 through the flexible connection b^9 and rigid pipe b^7 until the weight of the float b^6 and its contents overbalances the weight b^{12} , turning the lever b^2 on its pivot and closing the inlet-valve for the chamber. The cock a^4 in the pipe a' is then opened and the liquor in the auxiliary chamber is permitted to flow through the pipe a' and branch pipes a into the liquid-feeders above the evaporating-surface. As the liquor flows from the auxiliary chamber a^3 its level in the said chamber and in the float is lowered, and

the counterbalancing-weight b^{12} overcomes the weight of the float b^6 and again opens the inlet-valve to the chamber a^3 , permitting more weak liquor to flow into the vessel or chamber a^3 . The liquor on its passage through the evaporator is concentrated and is drawn from the evaporator by the pump c' through the pipe c and is forced through the outlet-pipes c^2 for the pump back into the auxiliary chamber a^3 if the cock or valve c^4 in the branch or discharge pipe c^9 remains closed. The partially-concentrated liquor returned by the pump into the vessel a^3 falls upon the distributor and mixes with the weak liquor from the supply-tank a^6 , so that the liquor below the mixing-plate in the vessel a^3 is of a higher specific gravity than the weak liquor in the tank a^6 . The liquor returned into the vessel or chamber a^3 helps to fill the same until the float b^6 overcomes the weight b^{12} and cuts off the supply from the tank a^6 . The cock c^4 remains closed until the liquor has attained the desired specific gravity, and when this has been effected the said cock may be more or less opened to discharge a quantity of the liquid. The greater portion of the liquid, being returned to the vessel a^3 , further mixes with fresh weak liquor from the tank a^6 . The supply of weak liquor, it will be noticed, is

automatically controlled by the level of the liquor in the vessel a^3 , and therefore the said vessel may, and preferably in practice will, have a vent-opening for the escape of air or vapor in the vessel a^3 , the vapor preferably being conducted into the weak-liquor tank a^6 35 by a pipe b^{20} , or, if desired, the vessel a^3 may be open at its top.

I claim—

In an evaporating apparatus, the combination, with an evaporator and a liquid-supply 40 therefor, of an independent auxiliary or mixing chamber connected to the said liquor-supply and to the evaporator and interposed between them, a valve to control the liquor-supply, a float connected to the supply-valve 45 and operated by the level of the liquid in the mixing-chamber, and a pump connected to the said evaporator and to the mixing-chamber, and a branch pipe connected to the discharge-pipe for the pump, substantially as 50 described.

In testimony whereof I have signed my name to this specification in the presence of two subscribing witnesses.

THOMAS GAUNT.
